(57) **CLAIM**

We claim the ornamental design for a dual cereal dispenser, as shown and described.

DESCRIPTION

FIG. 1 is a perspective view of the dual cereal dispenser according to the new design;

FIG. 2 is a right side view of the dual cereal dispenser shown in FIG. 1, the left side being substantially identical;

FIG. 3 is a front view of the dual cereal dispenser shown in FIG. 1;

FIG. 4 is a back view of the dual cereal dispenser shown in FIG. 1;

FIG. 5 is a top view of the dual cereal dispenser shown in FIG. 1; and,

FIG. 6 is a bottom view of the dual cereal dispenser shown in FIG. 1.

Features shown in broken lines in the drawings are not part of the claim.
